UNITED STATES PATENT OFFICE.

WALTER H. SCHRAMM, OF PITTSBURGH, PENNSYLVANIA, ASSIGNOR TO WESTINGHOUSE ELECTRIC & MANUFACTURING COMPANY, A CORPORATION OF PENNSYLVANIA.

INSULATOR.

Application filed March 10, 1927. Serial No. 174,131.

My invention relates to insulators and particularly to insulators that are subject to cantilever loads.

One object of my invention is to provide an insulator, of the above-indicated character, that shall be reinforced against fracture at a position in which breakage normally occurs under a cantilever load.

Another object of my invention is to provide means for materially strengthening an insulator against a cantilever load without impairing the insulating character of the insulator.

Another object of my invention is to provide insulating means for increasing the mechanical strength of an insulator of a given size without increasing the dimensions of the insulator.

A further object of my invention is to provide an insulator that shall be simple and durable in construction, economical to manufacture and effective in its operation.

In insulators for supporting cantilever loads, such as those for supporting bus-bars and the like, the main insulating bodies are subject to breakage, near the base ends thereof, beyond the outer ends of the usual metal collars or supporting members which surround the bodies. To reinforce the insulators against such breakage, it has heretofore been suggested to place metal members inside the base ends of the insulators. These inserts however, materially modify, or interfere with, the original insulating characteristics of the insulators.

When the above-mentioned metal inserts are not employed, it has been suggested to construct the insulators larger than the electrical requirements thereof in an endeavor to obtain greater mechanical strength.

However, in tests which I have conducted, it has been found that, in certain instances, increasing the size of the insulator does not provide the desired strength. For instance, it has been found that a cylindrical insulating member of a certain type, eight inches in diameter, is not appreciably stronger than a six inch insulator of the same type.

Therefore, it is my aim to provide an insulator that will be subjected to cantilever load in use, but that shall be no larger than necessary for effective mechanical operation and that shall, by the absence of the above-mentioned metal insert member, be more effec-

tive electrically than an insulator in which such an insert is employed.

Accordingly, in practicing my invention, I provide an insulator subject to cantilever load that is so reinforced by insulating means, in the form of insulating laminae or layers, across the line or zone of normal load fracture, as to greatly strengthen the insulator, without increase of size or impairment of its electrical properties.

The single figure of the accompanying drawing is a view, in longitudinal section, of an insulator constructed in accordance with my invention.

The insulator comprises, in general, a main insulating body portion or member 2, an outer-end member 3 for supporting a bus-bar or other conductor (not shown), a main supporting or base member 4 and a reinforcing element 5 constituting a portion of my invention.

The insulating body portion 2, preferably of porcelain or glass, is of substantially hollow cylindrical shape having outer surface-creepage corrugations or flanges 7 and an intermediate wall or web portion 8 which functions as an electrical barrier, as a cross brace against cantilever load and, also, to provide separate outer and base-end recesses or cup portions for the reception of the members 3 and 5, respectively.

The member 3, preferably constructed of metal, comprises an outer flange portion 10, disposed against the outer end surface of the insulating body 2, and a cup portion 11 closely conforming to the outer recess in the body and secured thereto by a body 12 of bonding material, such as cement, composition, or the like. An opening 14 in the flange 10 provides shoulders 15 to which elements (not shown) may be anchored or secured for holding a conductor or bus-bar in position.

The base member 4, preferably of metal, comprises a cylindrical collar or sleeve portion 17 surrounding, and bonded to, the base end of the insulating body 2 and a laterally projecting annular flange 18 having openings 19 for the reception of screws or bolts by which the insulator is mounted in position. The member 5, preferably of the same material as the insulating body member 2, is of inverted substantially cup-shape having side-wall portions 21 closely conforming, and disposed in slightly spaced relation, to the inner

longitudinal side surfaces of the base-end recess of the body 2. The closed-end wall 22 of the cup 5 is preferably of substantially flat discoidal form disposed substantially parallel to the adjacent surface of the web 8 and to a normal fracture zone across the body 2, as represented by a line X—X. A body of bonding material 23, such as cement, or the like, is placed in a preferably uniform layer between the outer surface of the cup 5 and the adjacent surfaces of the body 2. The cemented surfaces may be sanded or otherwise treated to ensure a more perfect bond with the cement or other bonding material.

15 In the above-described structure, the web 8 and the wall 22 of the cup 5 constitute cross braces against the cantilever load. The inner-end side walls, together with the side walls 21 of the cup 5, constitute a laminated 20 insulating structure which traverses the zone X—X of normal load fracture. Since laminated structures are stronger than solid structures of the same material and the cement body 23 is also usually as strong as, or 25 stronger than, the refractory bodies 2 and 5, the insulator is very materially strengthened across the fracture zone.

It is to be understood that the line X—X only approximately indicates the fracture 30 zone, the exact location of which depends upon the dimensions and other features of the sleeve 17 and other parts.

35 By my invention, a compact, durable and effective insulator is provided which is no larger than necessary for its exact mechanical and electrical requirements and is materially stronger than similar insulators heretofore used.

40 While I have shown and described a particular form of my invention, changes may be effected therein without departing from the spirit and scope thereof, as indicated by the appended claims.

45 I claim as my invention:

1. An insulator subject to cantilever load comprising an insulating member having a cupped base end and means for reinforcing the same against normal load fracture in-

cluding a cupped insulating member in said end.

2. An insulator subject to cantilever load comprising an insulating member having a cupped base end and means for reinforcing the same against normal load fracture including an insulating cup substantially conforming to the recess in said end and bonded to said end with its closed end adjacent to the bottom of said recess.

3. An insulator comprising a cylindrical insulating member subject to cantilever load and having a cupped base end, a metal supporting member therefor having a cylindrical portion surrounding the base end thereof and an insulating cup substantially conforming to the recess in said end and bonded to said end with its closed end adjacent to the bottom of said recess.

4. An insulator comprising a cylindrical insulating member subject to cantilever load and having a recessed base end, a metal supporting member therefor having a cylindrical portion surrounding said end, the arrangement of parts normally creating a load-fracture zone across, and adjacent to the outer end of, said metal cylindrical portion and an insulating cup in said recess having its closed end substantially parallel, and adjacent, to said zone.

5. An insulator comprising a hollow cylindrical insulating member subject to cantilever load, a metal supporting member therefor having a cylindrical portion surrounding the base end thereof, said insulating member having a transverse web portion across the hollow portion thereof outwardly beyond the outer end of said metal cylindrical portion and an insulating cup bonded in position in said base end having sides closely conforming to the inner side surface of the insulating member and an end wall parallel, and adjacent to, said web portion.

In testimony whereof, I have hereunto subscribed my name this first day of March, 1927.

WALTER H. SCHRAMM.
